SAMUEL ZULLO, OF JERSEY CITY, NEW JERSEY

PHONOGRAPH RECORDS PLAYING MACHINE

Application filed April 9, 1930. Serial No. 442,718.

The object of this invention is to provide a phonograph disk record playing machine particularly adapted for use in broadcasting and in the talking motion picture industry. 5 A particular object of the invention is to provide a machine for playing phonograph records, so arranged and constructed so as to completely eliminate all noises and sounds foreign to the musical reproduction. Another object of the invention is to provide means whereby the machine may be used to operate a motion picture machine in synchronism with the playing of a phonograph record. Other objects will appear as this specification proceeds while reference is had to the accompanying drawings in which 15

Figure 1 is a side elevation of a machine with parts broken away and in section and parts omitted.

Figure 2 is a detail view of the phonograph record carrying turntable, partly broken away.

Figure 3 is a detail view of parts shown in Figures 1 and 2.

Referring to the drawings, the phonograph record to be played, that is broadcasted is designated 1 and is carried by a turntable comprising a record supporting disk 2 and a turntable base 3. The supporting disk 2 is provided with the usual center stud or pin as shown. The two latter elements are connected in a manner permitting automatic centering and levelling of the supporting disk with respect to the turntable base, at the same time also eliminating all vibration from the record supporting disk and all noise due to the operating mechanism and associated parts.

To this end the disk 2 is supported on the base 3 by means of vertically disposed spring members, four in number. Each spring member, Figure 3, consists of two springs 4 and 5 carried by a rod 6. The spring 4 is interposed between the supporting disk 2 and

the turntable base 3. The other spring 5 is located beneath the base 3.

The rod 6 extends from the disk 2 and through the base 3. It carries a nut 7 whereby to adjust the tension of the springs 4 and 5. The aperture 8 in the base 3 is large enough to permit lateral movement of the disk 2 relative to the base 3 without disturbing the action of the spring member in supporting the disk 2.

The disk carries four lugs 10 and the base carries four lugs 11 in lateral spaced relation and in alinement. A rod 13 passes through each pair of lugs and carries two springs 14 and 15, the tension of which may be adjusted by a nut 16.

From this it will be seen that as the base 3 is rotated, it carries the disk 2 along, permitting lateral centering of the latter, which in turn rests upon and floats on the vertical spring members. In this manner all vibration from the driven member 3 is taken up by the spring members and the phonograph record is operated so as to eliminate all noise and vibrations from the driving mechanism and the machine.

It has been found that by this construction, the reproduction of sound from the record 1 is materially improved and noticeably superior particularly in broadcasting.

The turntable is carried by a shaft 16 which is suitably supported in a gear box 17 filled with oil and in which the shaft carries a worm gear 18 driven from a worm wheel 19 on a shaft 20. The latter is coupled to an electric motor shaft 21 by means of a flexible coupling 22 of suitable material and construction to eliminate as much as possible noise and vibrations from the motor 24.

The latter is supported on a bracket 25 which also supports the gear box and is secured to the upper end of a support 26 which is carried by a foot 27 in vertically adjustable relation by means of set screws 28. The foot is provided with levelling screws 29.

To still further steady the machine and avoid vibrations, there is provided an adjustable vertical brace 30 which rests on the foot 27 and supports the motor.

5 To the bracket 25 there is secured an upright 32 which carries the base 33 of the sound box arm 34 upon soft packings 35, which may be disks of rubber and felt or other like suitable material. The sound box 10 arm is pivoted at 37 and carries a suitable sound box 39 adapted by means of wires 40 to carry the sound from the phonograph record to a broadcasting or amplifying apparatus, not shown.

15 The bracket 25 may further carry a driving mechanism 44 comprising a shaft 42 driven by a worm and gear 43 and 45 from a coupling 46 similar to the coupling 22 connected to the motor shaft. The shaft 42 may be 20 used to operate a motion picture machine, not shown. In this manner a motion picture film may be synchronously operated with the phonograph record. The driving mechanism 44 may be detached if the machine is to be 25 used for broadcasting only.

A protecting shell or shield 49 is secured to turntable base and a guard rail 50 is provided to protect the machine in general.

From the foregoing it will be seen that the 30 machine may be set up, levelled and adjusted vertically for proper operation. A phonograph record may be played alone for broadcasting purposes, or may be played in synchronism with the driving mechanism for a 35 motion picture film.

The record supporting disk 2 floats on the springs 4 and 5 and is centered yieldingly and automatically by the horizontal springs 14 and 15.

40 While I have shown the invention in its preferred form, nevertheless it will be understood that changes and modifications may be made in the construction without going outside the scope of the appended claim.

45 I claim:

In a machine of the character described, in combination, a turntable shaft, a phonograph record operating turntable carried by said shaft and comprising a lower turntable 50 base rigidly secured to the shaft and an upper record supporting disk, devices interposed between the latter and the base for driving and supporting the disk consisting of four sets of horizontally disposed and supported 55 spring devices and four sets of vertically disposed and supported spring devices, each of said horizontal spring devices consisting of a lug depending from the record disk cooperating with an upstanding lug from the turntable base, said lugs being spaced and aligned in cooperative relation, a rod passing through said lugs, a coiled spring on said rod between the lugs and another coiled spring on the rod outside the lugs, a nut on said rod 60 to adjust the tension of the springs, each of 65

said vertical spring devices consisting of a rod depending from the record disk and extending through and below the turntable base, a coiled spring on said rod between the disk and the base and another coiled spring 70 on said rod below the base, a nut on said rod to adjust the tension of said vertical springs, the said spring devices being spaced alternately and circumferentially equidistantly on said turntable base and disk and means 75 for driving the said turntable shaft.

SAMUEL ZULLO.
